UNITED STATES PATENT OFFICE.

EDWARD B. ROTH, OF ST. LOUIS, MISSOURI.

RETORT FOR TREATING OIL SHALE.

Application filed June 30, 1926. Serial No. 119,543.

This invention relates to retorts for treating oil shale.

An object of the invention is to provide an improved retort for treating oil shale provided with means for moving the shale through the retort through zones of progressively increasing heat; to provide means for heating the retort from a separate and distinct furnace to avoid danger of explosion; to simplify the construction and mode of operation of the retort; to provide means for conducting heated air from the zone of maximum heat through pipes of progressively increasing length to the different zones; to provide equipment for indicating the degree of heat of the different zones; to provide a retort structure having a removable upper portion and removable agitators operating adjacent to the respective floors dividing the retort into the different zones; and generally to provide an improved retort for the purposes mentioned possessing all of the improvements and advantages made apparent by this specification, reference being made to the drawings, in which—

Fig. 1 is a vertical sectional view of my improved retort.

Fig. 2 is a cross sectional view showing one of the floors having openings therethrough near the center for discharge of the shale from one zone to another.

Fig. 3 is a cross sectional view showing one of the floors having openings therethrough near the inner confining wall of the retort.

The retort shown comprises an inner cylindrical wall 1 and an outer cylindrical wall 2 enclosing and spaced from the inner wall and forming a confined space 3 around the inner wall into which the vapors pass from the inside of the retort through series of openings 4 provided in the inner wall for that purpose. From the space 3 the vapors are withdrawn through an outlet passage 5 from the top of the retort. The top of the retort shown is preferably an integral structure comprising a dome-like inner wall 6 seating upon the inner wall 1 and having a flange 7 fitting within said inner wall; and a dome-like outer wall 8 spaced from the wall 6 and forming a space 9 between said inner and outer walls in communication with the space 3. The outer wall 8 is rigidly attached to the outer wall 2.

The shale is continuously fed to the upper end of the retort by a spiral conveyor 10

operating in a passage, a part 11 of which is shown as an integral extension of the top structure. Thus the shale is delivered into the upper zone of the retort which is separated from the next zone by a removable floor 12 having a series of openings 13 through which the shale is discharged to the next zone.

The next zone of the retort has a removable floor 14 provided with openings 15 through which the shale is discharged to the next zone, the removable floor 16 of which has a series of centrally disposed openings 17 for the passage of the shale to the next zone, the removable floor 18 of which has a series of openings 19 near the wall 1 through which the shale is discharged to the final zone having a bottom wall 20 through which the shale is discharged through a series of centrally disposed openings 21 into a receptacle 22 provided with an inclined shale withdrawal passage 23. A spiral conveyor 24 operates in the passage 23 and extends into the receptacle 22 and is operative to withdraw the shale waste from the receptacle 22.

An annular chamber 25 is provided in the space 3 between the inner and outer walls of the retort around the lower part of the lowest zone. Hot or superheated air is admitted to the chamber 25 through a pipe 26 and passes from said chamber 25 at a temperature of about 770° F. into the lowest zone of the retort through holes 27. Hot air conducting pipes 28 extend and form passages from the chamber 25 to the respective zones above the respective floors 12, 14, 16 and 18 of the retort. Each pipe is preferably controlled by a regulating valve 29. It is desirable too that the temperature in the compartment above the floor 18 be about 627° F.; and the compartment above the floor 16 about 417° F.; the compartment above the floor 14 about 367° F., and in the compartment above the floor 12 about 217° F.

In operation the shale passing to the respective zones through the openings 13, 15, 17 and 19, to a large extent, restricts the outward passage of hot air through said openings, thus permitting the various zones of the retort to be subjected to progressively increasing heat from the upper to the lowest zone. This is desirable because some of the vapors will be separated from the shale components and will rise under the influence of lower heat than will other vapors. In order to separate and remove the vapors that will

separate and rise under the influence of lower heat the zone into which the shale is first received is heated to a degree of heat lower than that of the next zone, and so on, 5 to the final zone into which the shale is received; which final zone is heated to the maximum degree of heat needed.

A shaft 30 extends vertically through the various zones of the retort having its lower 10 end supported upon a bearing 31 in connection with the bottom 20. A number of arms 32 extend from the shaft 30 in each compartment and rotate with said shaft. These arms support flights 33 designed and 15 arranged to propel the shale delivered into the respective compartments toward the openings 13, 15, 19 and 21 through the respective compartment floors. Thus, in the upper compartment, the conveyor 10 discharges the 20 shale near the wall 1 and the flights 33 agitate and move the shale to the openings 13, through which the shale drops onto the floor 14 of the next compartment near the shaft 30. In said next compartment the 25 flights 33 agitate and move the shale to the openings 15 through which the shale is discharged to the floor 16 of the next compartment, and so on.

This retort is provided with means for 30 indicating the temperatures of the various zones and, in the embodiment shown, such means comprises equipment of known use and application, the same including a pyrometer staff 34 extending into each zone and 35 connected by wiring 35 to a pyrometer 36. These staffs 34 are removable and extend through connecting tubular unions 37 between the inner and outer walls 1 and 2.

I am aware that the construction, arrangement and relationship of parts of the device 40 may be varied within equivalent limits and I contemplate such variations as may be deemed beneficial. I do not restrict myself unessentially, but what I claim and desire 45 to secure by Letters Patent is:—

1. A device for treating oil shale comprising a vertical retort having an outer casing wall, an inner casing wall spaced from the outer casing and having openings therein 50 communicating with the space between the walls, a number of floors within the inner casing provided with openings therethrough respectively, and forming compartments each of which communicates through said 55 first openings with the space between said walls, a rotatable vertical shaft extending axially through said inner casing, an agitator device attached to said shaft in each of said compartments, a chamber for receiving 60 heated gases between said walls around and opening into the lowest compartment, and pipes for conducting heated gases from said chamber to said other compartments, respectively.

65 2. A device for treating oil shale comprising

ing a vertical retort having an outer casing wall, an inner casing wall spaced from the outer casing and having openings therein communicating with the space between the walls, a number of floors within said inner casing provided with openings therethrough respectively, and forming compartments each of which communicates through said first openings with the space between said walls, a rotatable vertical shaft extending 70 axially through said inner casing, an agitating device attached to said shaft in each of said compartments, a chamber for receiving heated gas in said space between said walls around and opening into the lowest compartment, pipes for conducting heated gases from said chamber to said other compartments respectively, a material receiving receptacle opening into said lowest compartment, and means for removing materials 75 from said receptacle.

3. A device for treating oil shale comprising a vertical retort having a vertical series of compartments, mechanism for agitating and feeding material through said compartments successively and continuously, means forming a confined space around said compartments and in communication with said compartments respectively, means forming a chamber in said space opening into the 90 lowest compartment of the series, and pipes forming communication from said chamber to the respective compartments.

4. A device for treating oil shale comprising a vertical retort, a vertical series of compartments in said retort, mechanism for agitating and feeding material through said compartments successively and continuously, means forming a confined space around said 100 series of compartments communicating with said compartments respectively, means forming a chamber for receiving heated gases in said space and opening into the lowest compartment of the series, pipes forming communications from said chamber to the respective compartments, and means controlling the passage of heated gases from said chamber through said pipes to said compartments.

5. A device for treating oil shale comprising a vertical retort, a vertical series of compartments in said retort, means for agitating and feeding the material through said compartments successively and continuously, means for admitting heated gases to said compartments respectively, means for controlling the passage of the heated gases to said compartments respectively, and means forming a 115 confined space around said compartments to receive the vapors therefrom.

6. A device for treating oil shale comprising a vertical retort, a vertical series of compartments in said retort, means for agitating and feeding the material through said compartments successively and continuously,

means for admitting heated gases to said compartments respectively, means forming a confined space around said compartments to receive the vapors therefrom, means forming 5 a chamber for receiving heated gases in said space around and opening into the lowest one of said compartments, pipes for conducting heated gas from said chamber to the other compartments respectively, and means for 10 regulating the passage of heated gases through said pipes.

7. A device for treating oil shale comprising a vertical retort having an outer casing wall, an inner casing wall spaced from the 15 outer casing and having openings therein communicating with the space between the walls, a number of floors within the inner casing provided with openings therethrough respectively, and forming compartments each 20 of which communicates through said first openings with the space between said walls, a rotatable vertical shaft extending axially through said inner casing, an agitator device attached to said shaft in each of said compartments, a chamber for receiving heated 25 gases between said walls around and opening into the lowest compartment, and means for conducting heated gases from said chamber to said compartments, respectively.

8. A device for treating oil shale comprising a vertical retort having an outer casing wall, an inner casing wall spaced from the 30 outer casing and having openings therein

communicating with the space between the walls, a number of floors within said inner casing provided with openings therethrough respectively, and forming compartments each 35 of which communicates through said first openings with the space between said walls, a rotatable vertical shaft extending axially 40 through said inner casing, an agitating device attached to said shaft in each of said compartments, a chamber for receiving heated gas in said space between said walls around and opening into the lowest compartment, 45 means for conducting heated gas from said chamber to said compartments, respectively, a material receiving receptacle opening into said lowest compartment, and means for removing materials from said receptacle. 50

9. A device for treating oil shale comprising a vertical retort having a vertical series of compartments therein, mechanism for agitating and feeding material through said compartments successively and continuously, 55 means forming a confined space around said compartments and in communication with said compartments respectively, means forming a chamber in said space around and opening into the lowest compartment of the 60 series, means for conducting heated gases into said chamber, pipes for conducting heated gases from said chamber to said compartments, respectively, and means for regulating the passage of gas through said pipes.

EDWARD B. ROTH.
